UNITED STATES PATENT OFFICE.

BERNARD LURIE, OF NEW YORK, N. Y.

KEY-GAGE.

1,279,384.

Specification of Letters Patent. Patented Sept. 17, 1918.

Application filed October 16, 1917. Serial No. 196,890.

To all whom it may concern:

Be it known that I, BERNARD LURIE, a citizen of the United States, and a resident of the city of New York, borough of Manhattan, in the county of New York and State of New York, have invented a new and Improved Key-Gage, of which the following is a full, clear, and exact description.

The invention relates to gages used in duplicating keys for pin tumbler cylinder locks.

The object of the invention is to provide a new and improved key gage arranged to permit a locksmith or other person to quickly and accurately gage duplicate keys.

In order to produce the desired result, use is made of a row of adjustable gaging members, a movable key support adapted to support a key having cuttings to be gaged, and a row of setting members bodily movable with the said key support and adapted to engage the said cuttings and to register with the said gaging members.

A practical embodiment of the invention is represented in the accompanying drawings forming a part of this specification, in which similar characters of reference indicate corresponding parts in all the views.

Figure 1 is a front elevation of the key gage with a portion of the key support broken out and a part shown in section;

Fig. 2 is a transverse section of the same on the line 2-2 of Fig. 1 and showing the parts in gaging position;

Fig. 3 is a similar view of the same and showing the parts in setting position and with the key to be gaged removed;

Fig. 4 is a sectional plan view of the same on the line 4-4 of Fig. 1;

Fig. 5 is a perspective view of the adjustable member of the key guideway; and

Fig. 6 is a perspective view of the clamping nut of one of the clamping bolts.

The key gage is mounted on a suitably constructed frame 10 provided with a top bar 11 in which screw vertically disposed gaging screws 12 arranged in a longitudinal row. On the frame 10 below the gaging screws 12 is mounted to slide transversely a key support 13 provided with a longitudinally extending guideway 14 adapted to support the shank of the key 15, the cuttings 16 of which are to be gaged. The guideway 14 is provided with an adjustable member 20 to permit of adjusting the guideway for keys having shanks of different thickness. For

the purpose mentioned the member 20 is provided with transverse pins 21 mounted to slide in the main part of the key support 13 and in the latter screws a screw 22 extending through the adjustable member 20 and having a head 23 abutting against the outer face of the said adjustable member 20. By turning the head 23 of the screw 22 the movable member 20 can be readily adjusted in a transverse direction to narrow or widen the guideway 14 for keys of different thickness.

The cuttings 16 of the key 15 are adapted to be engaged at their bottoms by knife edges 25 formed on the lower ends of setting pins 26 provided at their upper ends with heads 27 adapted to register at their upper faces with the bottoms of the gaging screws 12, as will be readily understood by reference to Figs. 1 and 2. The setting pins 26 are mounted to slide up and down in bearings 30 each bearing having a rearwardly extending integral arm 31 mounted to swing laterally on a pivot pin 32 and held removably in a corresponding recess 33 formed in the top of the key support 13. By the arrangement described each bearing 30 can be readily swung sidewise so as to properly adjust the corresponding sliding pin 26 relative to the bottom of the corresponding cutting 16. After the bearings 30 have been adjusted according to the cuttings 16 of the key to be gaged at the time, the arm 31 of each bearing is fastened in place by the use of a clamping bolt 35 engaging the arm 31 intermediate the bearing 30 and its pivot 32. The bolt 35 extends through a longitudinal slot 36 formed in the top of the key support 13, and on the lower end of the bolt 35 screws a nut 37 having a rectangular offset 38 fitting into the slot 36 to hold the nut against turning. The head of the bolt 35 is provided with the usual slot for the application of a screw driver to permit of conveniently turning the bolt with a view to loosen the corresponding arm 31 for adjusting the same and to draw the clamping nut 37 tight after the adjustment is made to securely fasten the clamping arm 31 in the adjusted position.

By the arrangement described the setting pins 26 can be readily adjusted sidewise to correctly engage their knife edges 25 with the bottoms of the cuttings 16 of the key 15 to be gaged at the time. By reference to the drawings it will be noticed that six setting pins 26 and a corresponding number of gag-

ing screws 12 are shown, as most keys have five or six cuttings, but more setting pins engaging screws 12 may be used for keys having more than six cuttings. If a key has 5 only five cuttings the last bearing 30 to the left is swung sidewise to the left to move its setting pin 26 out of reach of the end of the key so as not to interfere with the proper gaging of the cuttings 16 in this particular key.

The forward movement of the key support 13 is limited by a screw 40 screwing into the back of the key support 13 and slidably engaging a bracket 41 attached to the back 15 of the frame 10 and projecting into the path of the key support 13 to limit the rearward movement thereof with a view to move the setting pins 26 into vertical alinement with the gaging screws 12, as will be readily 20 understood by reference to Fig. 2. It is understood that the head 42 of the screw 40 abuts against the back of the bracket 41 on shifting the key support 13 into forward position thus limiting the forward movement of the key support 13 (see Fig. 3). In order to prevent accidental upward movement of the key support 13 use is made of a screw 43 screwing in the bottom of the key support 13 and extending through a slot 44 formed in the base of the frame 10. The head 45 engages the under side of the base and thus limits the upward movement of the key support 13.

In using the key gage, the locksmith or 35 other operator pushes the key support 13 into the forward position shown in Fig. 3 and then inserts the key to be duplicated into the guideway 14 until the bottoms of the stop lugs 50 of the key abut against the 40 right-hand end of the adjustable member 20 of the guideway 14 (see Fig. 1). On inserting the key 15 the knife edges 25 of the setting pins 26 drop into the bottoms of the cuttings 16, as shown in Fig. 1. The 45 key support 13 is now moved into rearmost position and then the gage screws 12 are screwed down until their bottoms rest on the tops of the heads 27 of the several setting pins 26 engaging the cuttings 16 at the time 50 (see Figs. 1 and 2). When this has been done the key support 13 is moved forward to its forward position and then the key 15 is withdrawn from the guideway 14. A duplicate key is now made from a blank with 55 the cuttings 16 of approximately the same depth as the cuttings of the original key, and then the locksmith or other operator inserts this duplicate key in the guideway 14 so that the knife edges 25 of the setting pins 26 engage the cuttings 16 of this 60 duplicate key. The key support 13 is now moved rearwardly and the locksmith or other operator can now readily see which of the cuttings 16 are correctly made and which 65 are not by observing the position of the tops

of the heads 27 with the lower ends of the corresponding gaging screws 12. It will be noticed that when the key support 13 is moved rearwardly the heads 27 of the setting pins 26 engaging the cuttings 16 of improper depth abut against the fronts of the corresponding gaging screws 12 and hence the operator can see which of the cuttings 16 requires a further deepening and also the amount of the material that is to be removed 75 from the corresponding cutting to make the same the same depth as that of the corresponding cutting of the original key. After the operator has made his observations the key support 13 is moved back into forward 80 position and then the duplicate key is withdrawn from the guideway 14, after which the operator deepens the cuttings that need further deepening. The duplicate key is then reinserted in the guideway 14 and the 85 above described operation is repeated as many times as are necessary and until the key support 13 can be moved into extreme rearmost position with the tops of the heads 27 for the setting pins 26 fitting under the 90 bottoms of the gaging screws 12.

It will be noticed that by the arrangement described the locksmith or other operator is enabled to readily gage the cuttings 16 of the duplicate keys to allow the 95 locksmith or operator to reproduce the cuttings of the duplicate keys to accurately correspond to the cuttings of the original key.

The key gage shown and described is very simple and durable in construction and 100 is not liable to get easily out of order.

Having thus described my invention, I claim as new and desire to secure by Letters Patent:—

1. A key gage, comprising a row of adjustable gaging members, a key support laterally movable with respect to the row of gaging members and adapted to support a key having cuttings to be gaged, and a row of setting members bodily movable with the 110 said key support and adapted to engage the said cuttings and to register with the said gaging members.

2. A key gage, comprising a row of gaging screws, a key support having a guideway 115 for the insertion of a key to be gaged, a row of slidable setting pins on the key support and adapted to engage the cuttings of the key and to register with the said gaging screws.

3. A key gage, comprising a row of adjustable gaging members, a key support laterally movable with respect to the row of gaging members and adapted to support a key having cuttings to be gaged, and a row of setting pins 125 slidably loosely on the key support and adapted to engage the said cuttings, the said pins being adapted to register with the said gaging members.

4. A key gage, comprising a frame, a row 130

of gaging screws mounted in the said frame, a key support slidable on the said frame and provided with a guideway adapted to support a key having cuttings to be gaged, and 5 a row of setting pins slidable in the said key support and adapted to engage at one end with the said cuttings, the other ends of the said pins being adapted to register with the said gaging screws in one position of the 10 key support.

5. A key gage, comprising a row of adjustable gaging members, a key support laterally movable with respect to the row of gaging members and adapted to support a 15 key having cuttings to be gaged, bearings adjustably mounted on the said key support, and setting pins slidable in the said bearings and adapted to be seated in the said cuttings, the said setting pins being adapted to 20 be moved into register with the said gaging members on shifting the said key support.

6. A key gage, comprising a row of adjustable gaging members, a key support laterally movable with respect to the row of gaging 25 members and adapted to support a key having cuttings to be gaged, bearings provided with arms pivoted for adjustment on the said key support, means to secure the said arms in place on the key support, and setting pins slidable in the said bearing and adapted to be seated in the said cuttings, the 30 said setting pins being adapted to register with the said gaging members on shifting the said key support.

35 7. A key gage, comprising a frame, a row of vertical gaging screws screwing in

the said frame, a key support slidable transversely on the said frame and provided with a guideway for the reception of a key having cuttings to be gaged, a row of vertical bearings having angular arms pivoted for adjustment on the said key support, means for fastening the said bearing arms in place on the key support after adjustment, and setting pins having heads and slidable in the 40 said bearings, the pin heads being adapted to rest on the said bearings and being adapted to move in register with the said gaging screws, the lower ends of the pins being adapted to be seated in the said cuttings. 45

8. A key gage, comprising a frame, a row of vertical gaging screws screwing in the said frame, a key support slidable transversely to the row of gaging screws on the said frame and provided with a guideway 55 for the reception of a key having cuttings to be gaged, the said guideway being formed in part by an adjustable member to adjust the width of the guideway for keys of different thickness, a row of vertical bearings having 60 arms pivoted for adjustment on the said key support, means for fastening the said bearing arms in place on the key support for adjustment, and setting pins having heads and slidable in the said bearings, the pin heads 65 being adapted to rest on the said bearings and being adapted to move in register with the said gaging screws, the lower ends of the pins being adapted to be seated in the said cuttings.

BERNARD LURIE.
